APPARATUS FOR EXTINGUISHING FIRES

Howard G. Freeman, Worcester, Mass., assignor
to Rockwood Sprinkler Company, Worcester,
Mass., a corporation of Massachusetts

Application August 12, 1941, Serial No. 406,450

3 Claims. (Cl. 169—4)

The present invention relates to apparatus for extinguishing fires, and more particularly for extinguishing oil fires occurring in vessels such as transformers, open quenching vats, and the like.

The extinguishment of fires under such circumstances has presented a number of difficult problems. In the case of a transformer, for example, the fire often follows a short-circuit, the heat of which causes a hole to be formed in the top of the transformer by rupturing, cracking, or even melting the metal. Or an explosion may occur, which blows off the manhole cover. In any such case, the conditions are favorable for ignition of the oil vapors which rush out through the opening. Burning oil may rise over the top and run down the side walls, thus contributing to the difficulties by maintaining the contents of the transformer in a heated condition. Such burning oil prevents effective action by fire-fighting crews and also endangers adjoining structures.

According to the present invention, water in the form of fine sprays or mists is directed across the top of the vessel, but out of contact with the contents thereof, and also in a vertical direction to envelop the flaming oil which runs down the walls. The mist or spray in finely divided form lowers the temperature of the vapors by the vaporization of the water. The entire structure is blanketed over the top and around the sides by a dense mist or fog, through which the radiant heat cannot penetrate, and thus adjoining structures are satisfactorily protected.

In the accompanying drawing, Fig. 1 is a diagrammatic plan view of a fire protection installation for a large transformer; Fig. 2 is an elevation of the installation shown in Fig. 1; Fig. 3 is a sectional detail view of the preferred form of nozzle; and Fig. 4 is a bottom plan view of the nozzle shown in Fig. 3.

As shown in Fig. 2, a transformer 6 is mounted on conventional supports 8 on a base 10. The transformer is protected by a series of nozzle heads indicated generally at 12 in Fig. 1, and of a construction to be described later in detail. Around the base of the transformer is preferably arranged another series of somewhat similar heads 14. The heads 12 and 14 are connected by piping 16, through a supply pipe 18 and deluge valve 20, with a suitable source.

Each of the nozzle heads 12 is arranged to deliver a fine fan-shaped spray across the top of the transformer, and also a vertical spray which envelopes the side walls thereof. As shown in Fig.

1, the horizontal spray from each nozzle head is of a pattern indicated by the dotted lines. The patterns of the several horizontal sprays overlap above the transformer to produce a dense mist or fog directly over the burning oil. As shown in Fig. 2, the heads 12 are disposed only slightly above the top of the transformer, whereby substantially no water is actually directed into the interior of the transformer itself. The effectiveness of the installation depends on the action of the fine particles of water on the ignited vapors.

The nozzle heads 14, which are arranged around the base of the transformer in a manner similar to the heads 12, direct a horizontal spray against the base, to protect against the spread of burning oil from the base.

The main purpose of the vertical sprays is to hold the fire in check and to form a blanket which protects fire fighting crews and also any structures in the neighborhood. The horizontal sprays which play across the top constitute the chief means for extinguishing the fire. These sprays introduce finely divided water into the "base" of the fire (namely, the point at which the vapors issuing from the opening come into contact with the atmosphere). The small particles of water are quickly vaporized, and because of the high latent heat of water, act to carry the heat away rapidly. When the rate of absorption of heat by vaporization is faster than the rate of oxidation of the vapors, the fire is extinguished. Without the horizontal sprays, therefore, the vertical sprays would not be completely effective. On the other hand, the horizontally projected sprays should not in themselves be relied upon, since, if the fire has attained some headway before the spray is turned on, the presence of the burning oil on the side walls might be sufficient to keep the contents of the transformer at a sufficiently high temperature to maintain the fire. Accordingly, the combination of the horizontally projected sprays with the vertically projected sprays which envelop the fire has been found highly effective in rapidly extinguishing fires of a type which has resisted other methods of attack.

An important feature is the projection of the horizontal sprays into the vapors, and substantially out of contact with the liquid contents of the vessel. This results in the most effective use of the water, since the high latent heat is availed of to the maximum extent. Introduction of any considerable quantity of water into the liquid itself is not desirable, not only because of inef-

ficient use of the water, but also because increase in volume of the contents of the vessel may contribute to the spilling over of burning oil.

The preferred form of nozzle head 12 is shown in Figs. 3 and 4. This head comprises a fitting 22, having coupling threads 24 for attachment to the piping. A thick disc forming a nozzle member 26 is threaded into the end of the head, and a second nozzle member 28 is inserted in the bottom wall of the head. The nozzle members 26 and 28 are identical, and the description of one only will suffice. Each is provided with a milled internal slot 30 and an external slot 32 at right angles to the slot 30. The slots are cut approximately half way through the disc so that they intersect to form a rectangular orifice shown at 34 in Fig. 4. The water flows along the internal slot 30 toward the central orifice in streams indicated by the arrows in Fig. 3. The streams meet forcibly at the center of the slot, and the water is broken up into a fine mist or fog, which is projected outwardly through the central orifice, mainly in a plane perpendicular to the inner slot. From the nozzle 26, the spray is projected in a horizontal plane. As viewed in Fig. 3, the pattern is relatively narrow, but as viewed from below, as shown in Fig. 4, it fans out sufficiently to cover the top of the vessel, (see Fig. 1). The vertically projected sprays from the nozzles 28 are similar in shape, as indicated in Figs. 2 and 3, and are arranged so that the individual spray patterns overlap to produce a dense fog blanket surrounding the transformer.

Although the vertical spray patterns in Fig. 2 do not indicate actual contact of the water with the side walls, it will be understood that a considerable volume of what may be called drift fog moves into direct contact with the flames. Actual contact of all the water with the walls is not necessary, and in fact is not desirable, since the surrounding blanket of fine water particles is most effective for preventing transmission of radiant heat to the surroundings.

The heads 14 around the base preferably include the end nozzles 26 only, to direct horizontal sprays to act on burning oil which may have run down the side walls and started to spread over the ground.

For the nozzle head shown in Figs. 3 and 4, other types of nozzles capable of producing a projected fog may be substituted.

Although the invention has been described as employed in installations for transformer protection, it is equally suitable for other installations where oil fires in open vessels are likely to occur. For example, fires in large quenching vats present substantially the same problems as in the case of 10 transformers, and it has been found that the present invention is equally effective therewith.

Having described my invention, I claim:

1. Apparatus for extinguishing oil fires in vessels comprising a frame of piping surrounding the vessel, means for supplying water to said piping, and a plurality of nozzle heads connected to said piping, each head having a nozzle member to project a fan-shaped fog substantially in a horizontal plane above the vessel, and a second nozzle member to direct a fan-shaped fog in a generally vertical plane, the fogs projected from the several nozzles overlapping to cause the vessel to be substantially completely enveloped by fog.

2. Apparatus for extinguishing fires in vessels containing highly flammable fluids, comprising a frame of piping surrounding the vessel, means for supplying water to said piping, and a plurality of nozzle heads connected to said piping, said heads having a plurality of nozzles, certain of said nozzles being disposed to project a fine mist of water substantially in a horizontal plane above the vessel, others of said nozzles being disposed to direct a fine mist of water over the walls of said vessel, and the remainder of said nozzles being disposed to direct a fine mist of water over a substantial area surrounding the base of the vessel.

3. Apparatus for extinguishing fires in vessels containing highly flammable fluids, comprising a frame of piping surrounding the vessel, means for supplying water to said piping, and a plurality of nozzle heads connected to said piping, certain of said heads being disposed in the vicinity of the top of the vessel to project a fine mist of water across the top and over the walls of the vessel, and other heads being disposed adjacent the base of the vessel to envelop the base and to blanket an area surrounding said base with a fine mist of water.

HOWARD G. FREEMAN.
